UNITED STATES PATENT OFFICE.

MELVIN BANCROFT, OF WHITESTOWN, NEW YORK.

CLAMPING-MACHINE.

SPECIFICATION forming part of Letters Patent No. 303,909, dated August 19, 1884.

Application filed March 5, 1884. (No model.)

To all whom it may concern:

Be it known that I, MELVIN BANCROFT, a citizen of the United States, residing at Whites-
town, in the county of Oneida and State of
5 New York, have invented a new and useful
Bureau-Clamping Machine, of which the fol-
lowing is a specification.

My invention relates to improvements in
bureau or cabinet clamping machines, which,
10 with all the parts combined, I call a "bureau-
clamping machine."

The objects of my improvements are, first,
to provide a means of holding the several parts
of a bureau, or any similar case-work, in their
15 proper place during the work of securing the
several parts together; second, to provide a
means of bringing, with the greatest ease and
speed, the work under construction into the
several required positions, to facilitate the
20 work of the operator. I attain these objects
by the mechanism illustrated in the accompa-
nying drawings, in which—

Figure 1 is a vertical view of the entire ma-
chine, and also shows a piece of work in pro-
cess of construction. Fig. 2 is a top plan view
25 of the same. Fig. 3 is a detail view of back
of face-plates. Fig. 4 is a detail view of front
of face-plates. Fig. 5 is a vertical end view of
head-block, also of hand-wheel, slide, and cross-
30 sections of bed-plate. Fig. 6 is a side view of
the sliding box, and also of one of the stop-
pins.

Similar letters refer to similar parts through-
out the several views.

35 The bed-plate A and the head-blocks B and
C constitute the frame-work of the machine.
The bed-plate A is constructed with a groove
or track running the entire length of top side
to receive the guide on under side of head-
40 blocks B and C. The head-blocks B and C
can both be made to move longitudinally on
the bed-plate A; but I prefer to make the head-
block C stationary, and make only the head-
block B movable, and clamp or fasten by means
45 of bolts and nuts P at any point on bed-plate
A desired. The guides on under side of head-
blocks B and C, fitting the groove or track in
top of bed-plate A, keep the head-block in
perfect position to bring the centers exactly in
50 line with each other. The head-blocks B and
C are provided with face-plates G and K.

These face-plates are strongly webbed, as
shown, by the back side of face-plate G in
Fig. 3, to give sufficient strength for the press-
ure to be brought to bear upon them. The 55
face-plate K is attached to head-block C by
the round stem or shaft I, protruding from the
back side of the plate, (shown by dotted lines
in Fig. 1,) running into or through the head of
head-block C, which acts as a bearing-box in 60
which it revolves. It is secured in place by
the pin L, which passes through the head-block
C and fits in a groove in stem I. Secured in
this position the face-plate K will rotate ver-
tically, and can be stopped in any position by 65
means of the stop-pin M, passing through the
collar of head-block C into holes in back of
face-plate. The top or head of head-block B
is provided with a sliding box, E, Fig. 6. An
end view of sliding box E is shown by Fig. 5, 70
and Figs. 1 and 2 show it in position in the
head-block B. The sliding box E is moved
longitudinally by means of screw and hand-
wheel D. The sliding box E receives the stem
F, protruding from back side of face-plate G, 75
in like manner as head-block C receives stem
J of face-plate K, and in this position face-
plate G rotates vertically, and is stopped in
any position by means of stop-pin I. The
edges of face-plates G and K are each pro-
80 vided with several clamps, N. The clamps N
consist of a round corrugated pin or standard
with screws at one end, which screw into
threaded holes in edges of face-plates G and
K. On this corrugated pin an arm both turns 85
and slides freely. Through the other end of
this arm a screw with hand-wheel passes, with
a follower or plate on lower end of screw.
These clamps N are operated by swinging the
screw end of clamp or arm around over the 90
work to the point to be held in position, and,
turning the hand-wheel of screw, the follower
is brought to bear upon the work, and this,
raising the screw end of arm, causes the other
end of arm to catch or clutch on the corrugated 95
pin or standard, thus forming a complete
clamp that can be used at any point
needed.

To illustrate more fully the construction and
use of my invention, I show in Fig. 1 a bureau 100
or case, O, in process of construction. The
end pieces and cross-frames of a bureau having

been placed between the face-plates G and K, the hand-wheel and screw D are turned, which, operating upon sliding box E, forces the face-plates together, thus bringing the several 5 parts into their proper place and holding them perfectly square with each other. The clamps N are then brought into requisition to hold the side facings and other parts of the work in place during the operation of securing the 10 several parts together. While in this position the bureau is virtually hung between two centers, and by removing the stop-pins I and M the work may be turned vertically in any position to suit the convenience of the operator. 15

What I claim, and desire to secure by Letters Patent, is—

1. The clamps N, with corrugated and smooth spindles adjustable on the rim of the 20 face-plates G and K, in combination with those face-plates, both revolving and stationary, and the head-blocks B and C, both removable and stationary, and the hand-wheel and screw D, running through the head-block B or the 25 head-block C, or through both, operating the

sliding box E, all in combination substantially as described, and for the purposes set forth.

2. The bed-plate A, in combination with head-blocks B and C, movable and guided upon the bed-plate A, the revolving face-plates G and K, with supporting-axes F and J, sliding box E, hand-wheel and screw D, operating the box E, and the adjustable clamps N upon the rims of the face-plates G and K, all in combination substantially as described, and 30 for the purposes set forth.

3. The bed-plate A, in combination with head-blocks B and C, movable and guided upon the bed-plate A, the revolving face-plates G and K, with supporting-axes F and J, sliding 35 box E, hand-wheel and screw D, operating the box E, and the adjustable clamps N upon the rims of the face-plates G and K, all in combination and making one machine, substantially as described, and for the purposes set forth. 40

MELVIN BANCROFT.
